(No. Model.)

E. J. DEVINE.
ELECTRIC TRAIN SIGNAL.

No. 541,389.

Patented June 18, 1895.

UNITED STATES PATENT OFFICE.

EDWARD JAMES DEVINE, OF PORT ARTHUR, CANADA.

ELECTRIC TRAIN-SIGNAL.

SPECIFICATION forming part of Letters Patent No. 541,389, dated June 18, 1895.

Application filed December 11, 1894. Serial No. 531,522. (No model.)

To all whom it may concern:

Be it known that I, EDWARD JAMES DEVINE, a citizen of the Dominion of Canada, residing at the town of Port Arthur, in the district of 5 Thunder Bay and Province of Ontario, Canada, have invented a new and useful Electric Train-Signal, of which the following is a specification.

This invention contemplates certain new 10 and useful improvements in electrical signals for railway trains.

The object of the invention is to provide 15 simple and highly efficient means for indicating at each end of a train when there is a parting or breaking between any two of the cars. This I accomplish by providing a complete electric connection between all the cars of the train, a bell or signal being located in the cab or engine and also in the rearmost car 20 or caboose of a freight train. At the end of each car the electric wires are passed through circuit closers, provided with pivoted tongues and the respective wires of adjoining cars are coupled together. Upon a break between any 25 two cars said tongues fall and close the electric circuit, causing a signal to be given at one end of each of the parted sections.

The invention comprises the novel features 30 of construction and also the detail combination and arrangement of parts, substantially as hereinafter fully set forth and particularly pointed out in the claims.

In the accompanying drawings, Figure 1 is 35 a view in side elevation showing the end portions of two box-cars provided with my improvements. Fig. 2 is a vertical sectional view of one of the signal-boxes, showing the tongue extended in full lines and lowered in dotted lines. Fig. 3 is a rear-face view of said 40 box. Fig. 4 is a diagrammatical view of the circuit-wires. Fig. 5 is a slightly-modified arrangement thereof. Figs. 6 and 7 are enlarged views of the couplers, the former being in plan and the latter a vertical cross-sectional view.

45 Referring to the drawings, A, A', designate the frames of two cars of which a series constitute the train. In each car, it may be along the top thereof, is arranged a series of electric wires 1, 2, 3, and 4. At the end of each 50 car is a circuit closer *a*, which, in its construction, comprises a box or frame *a'* attached to the car and having an upper inclined top *a''*

and a front opening or cut away portion *a''*. At the top of this opening is hinged or pivoted a shield or tongue *a''*, which when lowered into perpendicular position fits in the opening or cut-away portion *a''*. A spring *a''* serves to force this shield or tongue downward. The four wires above noted are passed into the box or frame and also longitudinally 60 into the shield or tongue passing out through the outer end of the latter. These wires are insulated, save the wires 2 and 4 at the point *w* (and wires 1 and 3 in the next adjoining car) where they are designed to contact to close 65 the circuit when the shield or tongue is lowered. To enable this the wire 4 upon entering the box or frame is carried around the inner walls of the latter and across the lower portion of opening *a''*, while the wire 2 is preferably slightly bowed or projected inward from the tongue, as at *b*. I have shown these wires as forming the hinge or supports for the pivots of the shield or tongue. The extended ends of these wires beyond the end of the 70 shield or tongue are connected to an insulated 75 coupler *C*, which consists of four bent, or approximately U-shape (in cross-section) copper plates *d* embedded at *d'* in gutta-percha or its equivalent.

The plates of the coupler of one car are designed to fit over and engage the plates of the coupler of the adjoining car. A semi-cylindrical tube *d''* is attached to each coupler, whereby when two couplers are united a complete inclosing tube for the coupler plates is provided. These tubular members are held together by a clamp or collar *D* composed of two parts *e* having central curved portions *e'* and straight ends *e''*. These parts are drawn 85 together for uniting the tube sections by springs *e''*. When the couplers are united the corresponding wires of adjoining cars are connected together, thus forming a complete circuit with insulated connections between 90 every two cars. A shield *e''* at the end of the 95 car protects the parts from ice and snow.

It often happens that freight and passenger cars are turned end for end in traveling over different roads. Ordinarily this would result 100 in destroying the continuity of the electric wires in circuit as the wires of one car would not correspond with the same wires of an adjoining car. This difficulty is avoided by

changing the position of the wires in every second signal, as shown in Fig. 5, where the positions of the wires 1 and 4 and 2 and 3 are respectively changed. When the insulated 5 coupler of one car is being connected with that of another it will suffice to give each a quarter twist, and the respective wires will meet each other, thus establishing a complete electric connection between the different cars.

10 The bell and batteries are indicated at w' . It is preferred to arrange the same in both the engine cab and rear car or caboose, the wires 15 2 and 4 being, for example, in circuit with the former, and wires 1 and 3 with the latter. A 20 push-button may be provided at each of the points w^2 for signaling between the two ends of a train.

The operation of my invention is as follows: In the event of any break in the train the 25 couplers at that point are disconnected and the shield or tongue of the circuit closer, under its own weight, or the action of the spring thereon, is lowered, causing the uninsulated portion of one of the wires, as 2, to engage the 30 return wire, as 4, and thus close the circuit and cause the ringing of the signal bell, say in the cab of the engine. At the same time the tongue of the adjacent circuit closer is likewise lowered and the uninsulated portions 35 of wires 1 and 3 being brought into contact the signal is given at the other end of the parted train or section, say in the caboose. The train hands or employés are thus notified instantly there is a break in the train. As soon as the 40 shields or tongues of the circuit closers are elevated the circuits are broken.

The advantages of my invention are apparent to those skilled in the art to which it appertains and it will be particularly observed 45 that I have provided inexpensive means for signaling in the event of any break in a train, and that the same being simple cannot readily get out of order or be deranged.

I claim as my invention—

45 1. The herein-described improvement in train signals, consisting of wires in each car of a train connected in series, signals and batteries at each end of the train, in circuit with said wires, and devices at each end of a car, 50 said devices being provided with a fixed frame and a pivoted shutter, one of said wires being secured to the frame and also to the shutter, and another wire to the shutter, so that when the shutter drops said wires contact, substantially as set forth.

2. In a train signal, a series of wires, and a circuit closer provided with a frame and a movable shield or tongue, said wires being extended into or mounted on said frame and tongue, one of them having an uninsulated portion, another of said wires also having an uninsulated portion extending across the plane of said former uninsulated portion, as set forth.

3. In a train signal, a series of wires, a fixed frame into which said wires extend, and a movable shield or tongue to which said wires are also connected, one of said wires having an uninsulated portion extending from said shield or tongue, another of said wires having an uninsulated portion in said frame contiguous to said former uninsulated portion, both of said uninsulated portions being designed to contact when said shield or tongue is out of its normal position, substantially as set forth.

4. In a train signal, a series of wires, and a fixed frame into which said wires extend, the same consisting of a frame having an opening or cut away portion, a shield or tongue pivoted to said frame at the top of said opening, and a spring bearing on said shield or tongue, said wires also being carried by said shield or tongue and two of said wires being arranged so as to intersect the plane of each other and designed to contact when said shield or tongue is lowered, substantially as set forth.

5. In a train signal, a series of wires, circuit closers into which said wires extend having movable shields or tongues through which said wires are passed, two of said wires being arranged so as to intersect the plane of each other and designed to contact when said shield or tongue is lowered, and couplers for uniting the corresponding wires of adjacent cars, the same comprising metallic plates, inclosing tubes and clamps, substantially as set forth.

6. In a train signal, a series of wires, circuit closers into which said wires extend having movable shields or tongues through which said wires are passed, and couplers for uniting the corresponding wires of adjacent cars, the same comprising metallic plates embedded in gutta-percha at one end, semi-cylindrical tubes, and spring-held clamps encompassing said tubes, substantially as set forth.

EDWARD JAMES DEVINE.
